US0D1103382S

(12) **United States Design Patent** (10) **Patent No.:** **US D1,103,382 S**
(45) **Date of Patent:** **** Nov. 25, 2025**

(54) **SURGICAL DRAIN DEVICE**

(71) Applicant: **Standard of Care Corporation**,
Chicago, IL (US)

(72) Inventors: **Iliana E. Sweis**, Chicago, IL (US);
Bryan C. Cressey, Chicago, IL (US)

(73) Assignee: **Standard of Care Corporation**,
Chicago, IL (US)

(**) Term: **15 Years**

(21) Appl. No.: **29/947,490**

(22) Filed: **Jun. 14, 2024**

Related U.S. Application Data

(63) Continuation of application No. 18/047,529, filed on Oct. 18, 2022, which is a continuation of application No. PCT/US2022/016410, filed on Feb. 15, 2022.

(57) **CLAIM**

The ornamental design for a surgical drain device as shown and described.

DESCRIPTION

FIG. 1 is a perspective view of a surgical drain device showing our new design;

FIG. 2 is a left-side elevational view thereof;

FIG. 3 is right-side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines depict portions of the surgical drain device that form no part of the claimed design.

1 Claim, 5 Drawing Sheets
